SOLENOID CONTROLLED VALVE

C. Andrew Allen, Chatham, Ga., assignor to
S. A. Allen, Inc.

Filed Sept. 17, 1970, Ser. No. 25,043

Term of patent 14 years

Int. Cl. D23—01

U.S. Cl. D23—19

FIG. 1

FIG. 2

FIG. 3

FIG. 1 is a perspective view taken from the top, one end and one side of a solenoid controlled valve embodying my new design;

FIG. 2 is a perspective view taken from the bottom, side and end opposite those shown in FIG. 1; and

FIG. 3 is an elevational view taken from the end shown in FIG. 2.

I claim:

The ornamental design for a solenoid controlled valve, as shown.
